Primary Examiner — Brett Miller*Assistant Examiner* — Sara Michie Pottenger(57) **CLAIM**

The ornamental design for a painter's perch, as shown and described.

DESCRIPTION

FIG. 1 is a front left perspective view of a painter's perch showing my new design;

FIG. 2 is a bottom right perspective view thereof;

FIG. 3 is a right elevational view thereof;

FIG. 4 is a rear elevational view thereof;

FIG. 5 is a front elevational view thereof;

FIG. 6 is a top plan view thereof;

FIG. 7 is a bottom plan view thereof;

FIG. 8 is a reduced front left perspective view thereof; and,

FIG. 9 is a reduced right elevational view thereof.

The broken lines showing a ladder in FIGS. 8 & 9 are included for the purpose of illustrating environmental structure and forms no part of the claimed design.
